UNITED STATES PATENT OFFICE.

JAMES KIRKHAM, OF MILWAUKEE, WISCONSIN.

WINDOW-CLEANER.

SPECIFICATION forming part of Letters Patent No. 275,921, dated April 17, 1883.

Application filed January 5, 1883. (No model.)

To all whom it may concern:

Be it known that I, JAMES KIRKHAM, of Milwaukee, in the county of Milwaukee, and in the State of Wisconsin, have invented certain new and useful Improvements in Window-Cleaners; and I do hereby declare that the following is a full, clear, and exact description thereof.

My invention relates to devices for cleaning windows, and will be fully described hereinafter.

In the drawings, Figure 1 is a perspective view of my device with its lower end broken away. Fig. 2 is an edge view of it in position for cleaning a window-pane, and Fig. 3 is a detail.

My cleaner may be made of any elastic material; but I prefer to make it of wire. It consists of two arms, A A', joined together at one end, each arm being adapted to receive a sleeve, B, that may be adjusted up and down on it and secured in adjustment by a set-screw, b. Each sleeve B carries a bracket, B', that is in turn secured to a block, C, and this block is designed to receive a cleansing-pad, D, which may consist of sponge, rags, chamois-skin, waste, or any convenient material, and it may be secured in place by strong rubber bands d, or by strings, or by wires; or I may let a strip or strips of rubber into the face of each or either of the blocks, so that when I want rubber surfaces for the work to be done I can take off the pads D and leave the rubber exposed.

The arms of my device are set so as to have

a tendency to approach each other and cause the pads to clamp the window-pane between them when the cleaner is in position; but, that I may regulate the clamping-pressure of the pads, I may make the connection between either 40 or both of the pads extensible, as shown in Fig. 3, and secure the parts in adjustment by a set-screw, b'.

I prefer to make one of the arms—A', for instance—in two sections and join the sections 45 together by a right-and-left-handed threaded sleeve, a', so that when I desire to clean one side of a window I may detach the upper section and discard the rest of the cleanser.

It is unnecessary to describe the operation 50 of my device, as this is fully illustrated in Fig. 2 of the drawings.

What I claim as new, and desire to secure by Letters Patent, is—

1. In a window-cleaner, the combination, 55 with elastic arms, of vertically-adjustable pad-holders and means, substantially as described, for securing them in adjustment.

2. The pad-holders C, sleeves B, brackets B', and set screw or screws, in combination with 60 the arms A A', as set forth.

In testimony that I claim the foregoing I have hereunto set my hand on this 18th day of December, 1882, in the presence of two witnesses.

JAMES KIRKHAM.
